UNITED STATES PATENT OFFICE.

CECIL RHODES, OF BRADFORD, ENGLAND.

COLLAPSIBLE FRAMEWORK APPLICABLE TO HAMMOCK OR DECK CHAIRS.

Application filed November 17, 1923. Serial No. 675,366.

To all whom it may concern:

Be it known that I, CECIL RHODES, a subject of the King of Great Britain, residing at 594 Station View, Thornton, Bradford, 5 in the county of York, England, have invented certain new and useful Improvements in Collapsible Frameworks Applicable to Hammock or Deck Chairs, of which the following is a specification.

10 This invention relates to a collapsible framework for use in the construction of hammock or deck chairs. The usual construction comprises crossing and jointed together back and bottom frame members 15 carrying a suitable seat fabric between them, the back member being capable of adjustment to various inclinations by means of a cross-bar of a double-sided jointed supporting member engaging with one or other of 20 a series of pairs of notches or the like formed in the top edges of the opposite sides of the bottom frame member. The object of the present invention is to enable a hammock or deck chair of this description to be 25 slidably folded into a more compact compass than heretofore, and so facilitate transport. A further object of the invention is to provide an improved locking arrangement, preferably capable of adjustment, to 30 prevent the inadvertent collapsing of the chair when in use, and a further object of the invention is to provide a hammock or deck chair adapted to be instantly opened out into one of its erect positions.

35 According to this invention the side sticks or bars of the back frame member are each divided into two lengths or sections suitably connected so as to be capable of sliding lengthways one upon the other during the 40 closing and the opening of the chair.

The lengths or sections are preferably mounted one above the other and in close proximity to each other by means of metal sleeves one fixed near the inner end of each 45 section and through which sleeves the sections slide one upon the other. The inner end portions of the sections overlap each other sufficiently when the back frame is in its extended state to give rigidity to the 50 member.

The side sticks or bars of the bottom frame member—located on the inside of the sticks or bars of the back frame member—are each made in two lengths or sections,

the lower sections—or rearwardly-extending legs—being pivotally connected at the tops to the bottom ends of the upper sections of the back frame member. Instead of the usual supporting or strut member engaging with notches or the like in the top edges of the rearwardly-extending legs I provide supporting or strut links which may be bowed out towards the front of the chair to suit requirements, one at each side of the framework on the inside of same, pivotally connected at the upper ends to the tops of the lower sections—or forwardly-extending legs—of the back frame member and at the lower ends to the rearwardly-extending legs. The said supporting or strut links are preferably made of metal—springy steel painted or otherwise treated to prevent rust—and since the rearwardly-extending legs are not in the same vertical planes as the forwardly-extending legs these supporting or strut links are laterally bent or curved to facilitate the connection of same at their ends to the said legs.

The upper sections of the side sticks or bars of the bottom frame member are rearwardly extended and pivotally connected at or near the extended ends to the above mentioned supporting or strut links in such a manner that when the said sections—or side sticks or bars of the seat frame—rest upon the tops of the rearwardly-extending legs the seat frame projects out in a suitable position. The said side sticks or bars of the seat frame are provided on their bottom edges with a series of pairs of notches or the like one or other pair being engaged—when the chair is in use—by the top ends of the rearwardly-extending legs which ends are suitably shaped to take such notches.

The parts which are connected together in the usual manner by rivets are so arranged and their lengths so proportioned that when the chair is closed or in its collapsed state the sections fold together and greatly reduce the length of the chair in its collapsed or folded state.

To more fully describe my invention reference is made to the accompanying sheets of drawings, forming a part of this specification, in which similar reference numerals indicate corresponding parts in each of the views.

Figure 1 is a side elevation of a hammock

or deck chair made according to this invention, and Figure 2 is a plan view of the same.

Figure 3 is a longitudinal section of the chair showing the chair in another position.

Figures 4 and 5 are a side elevation and a plan view respectively of the chair in its folded or collapsed state.

Referring to the drawings, the back frames 10 comprises the two forwardly-extending legs 2 connected together by the cross-bar 2^a and the two side sticks 3 of the back connected together by the cross-bar 3^a. At or near the inner ends of the legs 2 and the side sticks 15 3 are secured the metal sleeves 2^b and 3^b respectively through which sleeves the side sticks 3 and the legs 2 respectively can slide lengthways one upon the other. The bottom frame, made in two portions or sections, 20 comprises the two rearwardly-extending legs 4 connected together by the cross-bar 4^a and the two side sticks 6 of the seat connected together by the cross-bar 6^a. The upper ends of the rearwardly-extending legs 25 4 are pivoted at 5 to the inner or bottom ends of the side sticks 3 of the back. The rear ends of the side sticks 6 of the seat are pivoted at 7 to the two side strut-links 8—preferably made of metal— 30 which are pivoted at 9 to the inner or top ends of the forwardly-extending legs 2 and at 10 to the rearwardly-extending legs 4 at or about the position shown. The bottom edges of the two side sticks 6 of the seat are, 35 as shown, formed with two pairs of notches 6^b one or other pair of which is engaged by the top ends 4^b of the legs, which are suitably shaped to receive same. In lieu of the two pairs of notches I can form one pair or 40 in order that the inclination or slope of the seat can be varied as desired a series of pairs of such notches can be formed. 12 is

the flexible material attached at the upper end to the cross-bar 3^a and at the lower end to the cross-bar 6^a.

A hammock or deck chair of this construction can be instantly brought into use and at the same time in one of its erect positions by simply taking hold of the cross-bar 3^a and lifting the chair, and when the chair is in use there is less liability of it collapsing as the locking device—the engagement of 4^b with 6^b—is retained in engagement by the direct weight of the occupant of the chair.

Claims:

1. In a collapsible hammock or deck chair, the combination of a back frame formed of sides and a top crossbar, and forward leg sections adjustably and slidably connected to said sides, rear legs pivoted to the back frame, links pivotally connecting the forward leg sections respectively to the rear leg sections, a seat frame comprising sides and a crossbar pivoted to the said links, and a flexible sheet attached to said top and seat frame crossbars.

2. In a collapsible hammock or deck chair, the combination of a back frame formed of sides and a top crossbar, and forward leg sections adjustably and slidably connected to said sides, rear legs pivoted to the back frame, links pivotally connecting the forward leg sections respectively to the rear leg sections, an adjustable seat frame comprising sides and a crossbar pivoted to the said links, the sides of the said seat frame each having notches in its underside for engaging with the upper end of the corresponding rear leg, and a flexible sheet attached to the said top crossbar and the crossbar of the seat frame.

In testimony whereof I affix my signature.
CECIL RHODES.
